UNITED STATES PATENT OFFICE.

ORREN H. TALBOTT, OF NEW PLYMOUTH, IDAHO.

WATER GATE.

Application filed September 23, 1921. Serial No. 502,831.

To all whom it may concern:

Be it known that I, ORREN H. TALBOTT, a citizen of the United States, residing at New Plymouth, in the county of Payette and 5 State of Idaho, have invented certain new and useful Improvements in Water Gates, of which the following is a specification.

This invention relates to water gates and is designed to cover a gate somewhat similar 10 in principle to the device covered in my companion application filed under even date but embodying structure which permits the device of the present invention to function differently from the device covered in my co- 15 pending application.

The principal object of this invention is to provide a simply constructed self-sustaining gate especially adapted for use in the laterals or tributaries of irrigating ditches.

20 A further object of the invention is to provide a gate which will permit "backing up" of the water to a predetermined level, provision being made to allow overflow of the water after a predetermined level has 25 been reached.

A further object of the invention is to equip the gate with a spillway which will project the water beyond the gate to thereby prevent backing or returning of the water 30 beneath the gate, the spillway being adjustable to vary the projection of the water.

The above and other objects of this invention will be in part described and in part understood from the following description 35 of the present preferred embodiment of the invention taken in connection with the accompanying drawings wherein:—

Fig. 1 is a front elevational view of a water gate constructed in accordance with 40 my invention.

Fig. 2 is a rear elevational view thereof.

Fig. 3 is a transverse sectional view taken on the line 3—3 of Fig. 1 and

45 Fig. 4 is a vertical sectional view taken on the line 4—4 of Fig. 1 and illustrating the application of the invention.

The device of this invention consists of a body plate generally designated 5 which may be of any desired configuration and is preferably constructed of non-corrosive metal. The corners at the lower end of the plate are beveled as indicated at 6 to facilitate anchoring of the plate in a lateral of an irrigating ditch as shown in Fig. 4.

55 The plate is reversely folded adjacent each

of its lateral margins to provide parallel inner guides 7 and parallel outer guides 8. These guides extend from the lower end of the plate to a point in proximity to the upper end of the latter. The upper end of 60 the plate has its margin rolled over, as indicated at 9, to provide a thickened portion serving as an abutment through the medium of which the plate may be more conveniently anchored in the lateral. An opening 10 is formed in the plate adjacent the upper terminal of the latter and approximately midway between the guides. The opening is shown at the present instance to be squared although it may be made of any 65 desired configuration dependent to some extent upon the use to which the gate may be put.

Slidably mounted in the guides 8 is a closure or slide 11 consisting in the present instance of a blank of metal the upper margin of which is bent at right angles to provide an operating flange 12 through the medium of which the slide may be moved through the guides. Upward movement of the slide 80 11 is limited by the member 9 at the upper end of the plate which lies in the path of movement of portions of the slide which extend beyond the terminals of the flange 12. However, downward movement of the slide 85 is permitted the full extent of the plate to permit the opening 10 to be completely uncovered.

In order to project water passing through the opening 10 for an appreciable distance 90 beyond the gate a spillway 13 is provided which in this instance consists of a single sheet of metal the opposite ends of which are bent upwardly at right angles and extended to provide corners 14 which are slidably mounted in the guides 7. The body of the plate between the sides thereof is bent downwardly at an inclination so as to admit the water for an obvious purpose. The rear margin of the spillway projects upwardly 95 beneath an overhanging lip 15 which latter is formed by turning over the lower wall of the opening 10. This lip limits upward movement of the spillway. As is apparent, however, the spillway is adjustable in the 100 guides 7 between the lip 15 and the bed of the stream.

This device is likewise formed by stamping in a well known manner following which the gate is assembled as above set forth. The 110

- assembled gate is then urged into the side walls and bed of the stream as partially illustrated in Fig. 4. The slide 11 may be positioned to completely close communication through the opening 10, as shown in Fig. 4 of the drawings or to expose merely a part of the opening to thereby permit overflow of the water above the gate, through the opening 10 into engagement with the spillway 13 and thence on the bed of the lateral. As above set forth the spillway is likewise adjustable to correspondingly vary the trend of the water passing thereover.
- 15 Various changes may be made in this device especially in the manner of constructing and assembling the plates. However, I have above described what now seems to be the preferred form of the invention but I am aware that minor changes may be made to produce the same or substantially the same result as that obtained by the present construction.
- 20 What is claimed is:—
- 25 1. A water gate for the laterals of irrigat-

ing ditches including a plate provided with an opening, and a spillway movably arranged on the plate and having its inception at the lower end of the opening and disposed at an inclination outwardly from said plate.

2. A water gate for the laterals of irrigating ditches including a self-sustaining plate arranged in the lateral and provided with an opening, said plate being reversely folded to provide inner and outer guides in its body, a slide movably mounted in said outer guides to completely or partially close communication through said opening, and a spillway mounted in said inner guides to project water passing through the plate opening, beyond the plate.

In testimony whereof I affix my signature in presence of two witnesses.

ORREN H. TALBOTT.
